UNITED STATES PATENT OFFICE.

WILLIAM B. FLEMING, OF PHILADELPHIA, PENNSYLVANIA.

AUTOMATIC ORGAN.

1,146,321.

Specification of Letters Patent. Patented July 13, 1915.

Application filed July 18, 1912. Serial No. 710,152.

To all whom it may concern:

Be it known that I, WILLIAM B. FLEMING, a citizen of the United States, residing in the city and county of Philadelphia, State of Pennsylvania, have invented certain new and useful Improvements in Automatic Organs, of which the following is a specification.

My invention relates to improvements in musical instruments of the general character of that illustrated in Patent No. 811,912, issued to me February 6th, 1906.

The object of my present invention is to provide means whereby the pedal organ may be played independently of the other organs of the instrument and thereby obviate the necessity of coupling devices such as have heretofore been employed, whereby the pedal organ has been played through the manual organ and through the manual tracker holes of an instrument such as is illustrated in my patent above mentioned.

In an instrument provided with my present improvement in which the pedal organ is played independently of the manual organ, the musical sounds are clearer, more definite and are free from that "muddled" sound which is noted when the pedal organ is played through the manual organ.

My invention comprehends the combination and arrangement of parts set forth in the specification, specifically pointed out in the claims and which are illustrated in the drawings. It is to be understood, however, that changes in the construction may be made within the scope of the claims without departing from my invention.

In the drawings which should be referred to for a more ready and complete understanding of my invention,—Figure I is a view showing the perforated music sheets and certain mechanism for operating the same in plan view and also showing a portion of the frame or casing of the instrument in section; and Fig. II is a diagrammatic view of a portion of the mechanism including sectional views of the action box, a tracker bar and a pedal chest.

In the drawings, 1 designates perforated music sheets which are mounted upon rolls 3 and 4 supported upon portions 5 and 6 of the wooden casing or frame portion of the instrument. The said sheets are caused to travel over the tracker bars 7 by means of sprocket chains 8 and gear mechanism 9 synchronously and in known manner. The

tracker bars 7 are provided with manual organ tracker holes or ducts 10 and with pedal organ tracker holes 11. Each of the manual tracker holes or ducts is connected in known manner to mechanism for operating the manual organ and other parts which may be coupled thereto.

Each of the pedal holes or ducts is connected directly to mechanism for operating the pedal organ. There are sixteen of these extra holes or ducts 11 in each tracker bar, making a total of thirty-two whereby the thirty-two notes of the pedal organ may be played independently of the sixty-one notes of the manual organ, whereby the tones produced thereby are clear and distinct. This result is impossible of accomplishment where the pedal organ is played through the manual organ, the former being coupled to the latter in a well-known manner.

In Fig. II, 15 designates a tube constituting a passage-way or line from one of the pedal holes or ducts 11 to a passage-way 16 in the action regulating box. 17, 18 and 19 designate chambers in the said box which are under suction, that is to say, from which the air is being drawn by any suitable means not shown. 20 designates a chamber which is in communication with the atmosphere by means of a duct 21. The passage-way 16 is in communication with the chamber 17 through a bleed hole 22. The presence of the hole permits the equalization of the air pressure in the chamber 17 and passage-way 16 for a purpose which will be hereinafter described.

25 designates valve stems supported upon primary pouch pneumatics only one of which, 26, is shown. It will be understood that there are as many of these pneumatics and valve stems as there are keys in the organ. The said pneumatic 26 which is shown in Fig. II is in communication with the passage-way 16 through an opening 28.

30 designates a passage-way which is adapted to be placed in communication either with the chamber 17 or the chamber 20 through holes 31 and 32. At its opposite end the said passage-way 30 is in communication with a secondary pneumatic 33 situated in the suction chamber 19.

Assuming that the hole or duct 11 through the tracker bar 7 shown in Fig. II is closed, it will be understood that by reason of the communication through the hole 22 between the passage-way 16 and the

chamber 17 the pressure in said passage-way and the said chamber will be equalized with the result that the primary pouch pneumatic 26 collapses or falls and permits the valve stem 25 to occupy the position illustrated in Fig. II in which case the valve 34 drops down to open the hole 31 thereby opening the communication from the passage-way 30 into the chamber 17 with the result that the secondary or power pneumatic 33 is collapsed.

When the pneumatics and the valves are in the position indicated in the drawings it will be observed that the contact spring 35 is out of contact with the contact member 36. The position of the contact spring 35 is controlled by the reciprocating movement of the rod 37 which is carried upon the secondary pneumatic 33. The inflation and collapsing of said pneumatic causes reciprocating movement of the rod 37 and a consequent oscillating or pivotal movement of the spring contact member 35. The upward movement of the said spring is limited by the stop 38. When the sheet 1, however, has been moved so that a perforation therein is in registry with the hole or duct 11 so that air enters the tube 15 and thence into the passage-way 16 the primary pneumatic 26 will become inflated raising the valve 34 to close the holes 31, lifting the valve 40 to open the holes 32 and thus effecting communication of the passage-way 30 with the chamber 20 simultaneously with the closing of the holes 31. The result of this is that outside air enters the secondary pneumatic 33 and in view of the fact that the chamber 19 is under suction the said secondary pneumatic is inflated and expanded by the entry of air at normal pressure thereinto so that the contact member 36 closes the circuit 41 which includes the electro magnets 42 situated in the chamber 43 which chamber is in communication with the wind box or pedal chest 44 through a hole 45 indicated by dotted lines. The said pedal chest 44 and the chamber 43 are continually supplied with air from a bellows (not shown) during the time that the organ is in operation. The chest 44 operates the pedal organ. When the circuit is closed in the manner above set forth the electro magnet 42 is energized thereby attracting and drawing to it its armature 46 which closes the opening between channel 47 and the chamber 43 and opens communication between channel 47 and channel 48 thereby permitting pneumatic 50 to exhaust to the open air. For the details of construction of this armature and the manner of its operation reference may be had to United States Patent No. 982,419, issued to me January 24, 1911.

To the bottom of pneumatic 50 is rigidly affixed an arm 51 to which is connected rod

52 to which are attached pallets or valves 53 and 54. Rod 52 is held normally depressed by spring 55. When the pneumatic 50 is exhausted the rod 52 is raised against the pressure of spring 55 and carries the pallet or valve 53 into position to close the port 56 thereby closing communication between the pedal chest or wind box 44 and channel 57 and at the same time it carries pallet or valve 54 away from the port 58 so that the channel 57 is in communication with the outside air. At the same time that the pneumatic 50 exhausts and collapses to cause movement of the rod 52 and the parts associated therewith as above described the pneumatic 60 also exhausts through the channel 57 and collapses and by means of rod 61 carrying the pallets or valves 62 and 63 closes port 64 which forms communication between pedal chest or wind box 44 and the channel 65 and opens port 66 thereby permitting pouch pneumatic 67 to exhaust through channel 65. When the pouch pneumatic 67 is exhausted it operates valve or pallet 68 to open communication between the wind chamber 69 and channel 70 thereby permitting the air from the chamber 69 to pass into and through channel 70 and operate pedal organ pipe 71.

It will be understood that the train of mechanism herein shown and described for operating the organ pipe 71 will be duplicated for each of the other thirty-one pipes of the pedal organ.

As in the construction shown in Patent No. 811,912, I have provided long and short perforations 72 upon the edge of the perforated music sheets which coöperate with the two outside holes or ducts 73 upon the respective tracker bars for controlling mechanism whereby the two sheets are caused to travel synchronously. The mechanism for this purpose is fully described in said patent and is not shown herein.

By the provision of sixteen holes or ducts 11 in each of the tracker bars 7 having communication directly with the pedal organ mechanism and which holes or ducts are in addition to the sixty-one tracker holes or ducts for the manual organ, I am enabled to play the pedal organ entirely independently and separately from the manual organ. The result of this arrangement whereby the manual and the pedal organs are played separately and independently of each other is to obviate the "muddled" sound produced when the pedal organ is played through the manual organ by means of known coupling mechanism.

It will, of course, be understood that the music sheets 1 are provided with perforations corresponding to the manual tracker holes or ducts and the pedal tracker holes or ducts. It will also be understood that the manual tracker ducts or holes are in com-

munication with the proper mechanism for operating the manual organ notes, such communication and mechanism being substantially as that shown between the pedal organ tracker holes and the pedal organ pipe 71.

I claim:—

1. In an automatic organ the combination of a manual organ, a pedal organ, two tracker bars each having a plurality of ducts, means for placing certain of the said ducts in each of the said tracker bars in communication with mechanism for operating the manual organ, means for placing certain other of the said ducts in each of the said tracker bars in communication with mechanism for operating the pedal organ, music sheets each provided with perforations for coöperating with the ducts in each of the said tracker bars, and means for feeding the said sheets synchronously over the said bars.

2. In an automatic organ, the combination of a manual organ, a pedal organ two tracker bars each having ducts therein, connections between certain of the said ducts in each tracker bar and the manual organ, connections between certain other of the said ducts in each tracker bar and the pedal organ, two music sheets having perforations therein for coöperating with the ducts in the said tracker bars, and means for feeding the said sheets synchronously over the said bars.

3. In an automatic organ, the combination of a manual organ, a pedal organ two tracker bars each having a plurality of ducts therein, means for directly connecting certain of the said ducts in each tracker bar with the mechanism of the manual organ and certain other of the said ducts in each tracker bar with the mechanism of the pedal organ, and two music sheets each having perforations therein for coöperating with the ducts in the said tracker bars, and means for feeding the said sheets synchronously over the said bars.

Copies of this patent may be obtained for five cents each, by addressing the "Commissioner of Patents.
Washington, D. C."

4. An automatic organ comprising a manual organ and a pedal organ of thirty-two notes, two tracker bars with ducts and connections from each bar to parts of both organs, each bar having sixteen connections to the pedal organ, two music sheets perforated to coöperate with the tracker bars respectively, and means for feeding said sheets synchronously over the bars. 45 50

5. An automatic organ comprising a manual and a pedal organ two tracker bars each provided with a plurality of ducts, means whereby certain of the said ducts in each of the said bars are placed in communication with a manual organ, means whereby sixteen of the ducts in each of the said bars are placed in direct communication with a pedal organ, two music sheets perforated to coöperate with the respective tracker bars, and means for feeding said sheets synchronously over the bars. 55 60 65

6. An automatic organ comprising a manual and a pedal organ two tracker bars each being provided with perforations having connection with a manual organ and sixteen additional perforations having connection with a pedal organ, connections between the said tracker bars and the respective organs, two music sheets each having perforations for coöperating with the ducts having connection with the manual organ 70 75 and also having perforations for coöperating with the ducts having connection with the pedal organ, and means for feeding the said sheets synchronously over the bars.

In testimony that I claim the foregoing as my invention, I have hereunto signed my name this 16th day of July, A. D. 1912. 80

WILLIAM B. FLEMING.
